UNITED STATES PATENT OFFICE.

JOSEPH CHASSAING, OF CHICAGO, ILLINOIS, ASSIGNOR TO SHIRAS ELECTRIC COMPANY,
OF ST. LOUIS, MISSOURI, A CORPORATION OF MISSOURI.

DESIGN FOR A LIGHTING-FIXTURE.

46,564.

Specification for Design.

Patented Oct. 20, 1914.

Application filed April 21, 1914. Serial No. 833,578. Term of patent 14 years.

To all whom it may concern:

Be it known that I, JOSEPH CHASSAING, a citizen of the United States, residing at Chicago, Illinois, have invented a new, original, and ornamental Design for a Lighting-Fixture, of which the following is a specification, reference being had to the accompanying drawing, forming a part thereof.

The figure is a perspective of a lighting fixture showing my new design.

I claim:

The ornamental design for a lighting fixture, as shown.

JOSEPH CHASSAING.
